C. STEENSTRUP.
ELASTIC FLUID TURBINE OR TURBINE DRIVEN UNIT.
APPLICATION FILED JULY 3, 1920.

1,416,760.

Patented May 23, 1922.

Inventor:
Christian Steenstrup,

His Attorney.

UNITED STATES PATENT OFFICE.

CHRISTIAN STEENSTRUP, OF SCHENECTADY, NEW YORK, ASSIGNOR TO GENERAL ELECTRIC COMPANY, A CORPORATION OF NEW YORK.

ELASTIC-FLUID TURBINE OR TURBINE-DRIVEN UNIT.

1,416,760.

Specification of Letters Patent. Patented May 23, 1922.

Application filed July 3, 1920. Serial No. 393,932.

To all whom it may concern:

Be it known that I, CHRISTIAN STEENSTRUP, a citizen of the United States, residing at Schenectady, in the county of Schenectady, State of New York, have invented certain new and useful Improvements in Elastic-Fluid Turbines or Turbine-Driven Units, of which the following is a specification.

10 The present invention relates to elastic fluid turbines or turbine driven units and has for its object to provide an improved structure and arrangement for supporting such machines whereby while rigidly held 15 in alignment they are at the same time free to expand and contract axially in response to temperature changes.

For a consideration of what I believe to be novel and my invention, attention is directed to the accompanying description and the claims appended thereto.

In the drawing, the figure is a side elevation of a turbine driven unit embodying my invention, the drawing being of a diagrammatic nature.

In the present instance, I have shown my invention in connection with a unit comprising an elastic fluid turbine 5 which may be of the radial flow type and may have two 30 oppositely rotating rotors driving respectively driven machines 6 and 7, for example, electric generators. The exhaust conduit of the turbine is indicated at 8 and it has a flange 9 which may be bolted directly to the inlet conduit of a condenser.

Now, according to my invention, I support the turbine by means of links and levers in such manner that while it is held from lateral movement and kept axially aligned it is 40 at the same time free to expand and contract axially and also radially. To this end, I support the unit by means of levers 10 and 10^a which at one end are pivotally connected to the unit directly as indicated at 11 and 45 11^a, and at the other end are pivotally connected thereto through the intermediary of links 12 and 12^a. The direct connection 11 and 11^a are preferably next adjacent the center of the unit and the casing of the unit 50 may be provided with suitable ears or lugs 13 and 13^a to which the levers are pivoted. The link connections are preferably adjacent the ends of the unit, the casing being provided with ears or lugs 14 and 14^a to 55 which the upper ends of the links are pivot-

ally connected. Levers 10 and 10^a are directly below the unit and there may be lugs 13 and 13^a and links 12 and 12^a on each side of the levers so as to provide a symmetrical support for the unit. One of the levers, as 60 lever 10, is pivotally supported directly on an arm 15 carried by a bed plate 16; the other lever, as the lever 10^a, is pivotally supported between its ends by bed plate 16 through the intermediary of a link 17. Bed 65 plate 16 is shown as being mounted on a foundation 18.

With the above described arrangement it will be clear that the lever 10 holds the unit from axial movement as a whole relatively 70 to bed plate 16, but the links and levers permit the unit to expand and contract axially due to temperature changes, the expansion taking place in each direction from the pivot point 11. The unit is also free to expand 75 and contract radially.

In accordance with the provisions of the patent statutes, I have described the principle of operation of my invention, together with the apparatus which I now consider to 80 represent the best embodiment thereof, but I desire to have it understood that the apparatus shown is only illustrative and that the invention may be carried out by other means.

What I claim as new and desire to secure 85 by Letters Patent of the United States, is:—

1. In combination, a unit which when in operation is subject to changes in temperature, a bed, and means comprising axially extending levers which support the unit on 90 the bed, said means permitting the unit to expand axially due to temperature changes.

2. In combination, a unit which when in operation is subject to changes in temperature, a bed, and means comprising axially 95 extending levers and links which support the unit on the bed, said means permitting the unit to expand axially due to temperature changes.

3. In combination, a unit which is subjected to temperature changes, a bed, and means supporting the unit on the bed comprising an axially extending lever pivoted intermediate between its ends on the bed, the ends of the lever being pivoted to the 105 unit at axially spaced points.

4. In combination, a unit which when in operation is subject to changes in temperature, a bed, and means supporting the unit on the bed so the unit may expand and con- 110

tract axially, said means comprising levers which are pivotally connected at their two ends to the unit, one of said levers being pivotally supported between its ends directly by the bed, and a link pivotally connected at one end between the ends of another lever and pivotally connected at its other end to the bed.

5. In combination, a unit which when in operation is subject to changes in temperature, a bed, and means supporting the unit on the bed so the unit may expand and contract axially, said means comprising two

lever members each pivoted at one end adjacent the center of the unit and extending toward an end thereof, links pivotally connecting the other ends of said lever members to the unit, means pivotally supporting one of said lever members directly on the bed and forming a fulcrum for it, and a link 15 through which the other lever member is pivotally supported on the bed.

10 In witness whereof, I have hereunto set my hand this first day of July, 1920.

CHRISTIAN STEENSTRUP.
